UNITED STATES PATENT OFFICE.

OTTO M. BLIZZARD, OF DAYTON, OHIO.

WEATHER-STRIP FOR CASEMENT-OPENINGS.

1,184,310.

Specification of Letters Patent.

Patented May 23, 1916.

Application filed October 30, 1915. Serial No. 58,765.

To all whom it may concern:

Be it known that I, OTTO M. BLIZZARD, a citizen of the United States, residing at Dayton, in the county of Montgomery and State of Ohio, have invented a new and useful Improvement in Weather-Strips for Casement-Openings, of which the following is a specification.

This invention relates to a new and useful improvement in weather strips for casement openings.

The principal object of the invention is to provide for a swinging window or door, without interfering with the operation of either, a weather strip which will effectively prevent any water from passing through the opening between the sill and the base of the sash. No matter how violently water is blown or otherwise forced against the lower portion of the sash, it will be completely intercepted by my flanged strips and thereby deflected to the sill by which it will be further directed away.

The preferred form of embodiment of my invention is illustrated in the accompanying drawings, of which—

Figure 1 is a sectional view of my new water deflecting device applied to a sash and sill for a swinging window. Fig. 2 is a front elevational view thereof. Fig. 3 is a plan view of the bottom of the gutter, showing the slots through which the deflected water drops upon the sill. Fig. 4 is a front view of the outside bracket for clamping the water-receiving portion of the device to the window frame. Fig. 5 is a front view of the inside bracket for clamping said water-receiving portion of the device to the window frame. And Fig. 6 is a view, partly in section, showing how the water-receiving portion of the device is clamped by the said brackets to each side of the said window frame.

Throughout the specification and drawings, similar reference characters denote corresponding parts.

In a detailed description of the preferred form of embodiment of my invention, the numeral 1 designates the sash of a swinging window 2, and 3 the sill therefor. Countersunk in the base portion of the sash 1, a short distance above the stool 4 of the sill 3, is a channel member or water-shed 5. This channel member preferably comprises a flat metallic piece bent at its upper end to form a short downwardly inclined roof

portion 6, and at its lower end to form a downwardly inclined flange portion 7 whose purpose will be hereinafter described. The flat portion of the channel member 5 is 50 countersunk in the base of the sash 1, and secured thereto by means of screws 8.

Secured to the stool portion 4 of the sill 3, by means of screws 9, is a gutter 10. This gutter preferably comprises a flat metallic piece which extends a sufficient distance above the sill 3 to be engaged by the swinging sash 1. It is then bent outwardly and downwardly to form an inclined bottom portion 11 containing near its outer edge a plurality of elongated slots 12 preferably in longitudinal alinement with each other. (See Figs. 1 and 3). The metallic piece is then bent upwardly to form a vertical portion 13, and then upwardly and 75 inwardly in a preferably crooked manner to provide a flange portion 14 which extends sufficiently close to the countersunk portion of the channel member 5 to form therewith an elongated opening 15 for a purpose to be hereinafter described.

To assist the screws 9 in firmly holding the flange portion 14 of the gutter 10 in the position just referred to, brackets 16 and 17 are provided. A pair of these brackets 85 is employed to clamp each end of the gutter 10 to its respective side 18 of the window frame. The bracket 16 comprises a flat metallic piece which is notched on one side to conform to the exterior contour of the gutter 10, while the bracket 17 consists of a smaller metallic piece having a notched side which conforms to the interior contour of said gutter. With one end of the gutter 10 firmly clamped between them, the bracket 16 is made fast to the side of the window frame opposite said gutter end by means of screws 19, while the bracket 17 is secured to said frame by means of screws 20. There are two pairs of these brackets, 100 one pair for each side of the window frame, and in conjunction with the screws 9, they firmly maintain the gutter 10 in the position before described.

The operation of the device is as follows: 105 As will be observed from Fig. 1, the end of the flange portion 14 is disposed a short distance below the roof portion 6 of the water shed 5. As the window to which said shed is applied, is a swinging one, it is practically impossible to make the opening between said roof portion 6 and flange por-

tion 14 watertight, since it would make the opening and closing of the window a difficult operation. Therefore the elongated opening 15 is provided to enable any water 5 that may be blown or otherwise forced in between said roof portion 6 and flange portion 14 to drop upon the flange portion 7 of said water shed.

Any water passing through the opening 10 15, will be deflected by the flange portion 7 of the water shed 5, upon the inclined bottom portion 11 of the gutter 10, whence it will drip through the slots 12 upon the inclined portion of the sill 3 and by the 15 latter be directed away. Thus there is no danger of any water seeping or otherwise passing through the bottom opening between the sill and sash to the interior of a room, nor does this water-deflecting device 20 interfere in any way with the opening and closing of the window to which it is applied. And it matters not with what violence rain may be blown into the aforesaid opening between said roof portion 6 and 25 flange portion 14, its force will be broken thereby and the water permitted to pass through the opening 15 to the flange portion 7 of said water shed, whence it is directed by the latter through the slots 12 to 30 the outer portion of the sill 3.

I do not wish to be limited to the details of construction and arrangement herein shown and described, and any changes or modifications may be made therein within 35 the scope of the subjoined claims.

Having described my invention, I claim:

1. In a device of the class described, a swinging sash, a channel member countersunk in the outside base portion thereof, a 40 stationary sill for said sash, an elongated gutter secured to said sill and extending upwardly therefrom a sufficient distance to be engaged by the outside base portion of said sash, a downwardly inclined bottom for said 45 gutter containing an opening for the release of water therefrom, and a flange extending upwardly and inwardly from the bottom of said gutter, to the interior of said channel member, substantially as described.
2. In a device of the class described, a 50 swinging sash, a channel member countersunk in the outside base portion thereof, a stationary sill for said sash, an elongated gutter secured to said sill and extending 55 upwardly therefrom a sufficient distance to be engaged by the outside base portion of said sash, a downwardly inclined bottom for said gutter containing an elongated opening therein, and a flange extending upwardly 60 and inwardly from the bottom of said gutter, a sufficient distance within the interior

of said channel member, to form with the countersunk portion of the latter, an opening for the admission of water to the interior of said gutter, said channel member 65 having its lower flange portion inclined outwardly and downwardly a sufficient distance to direct said water to the slotted portion of the bottom of said gutter, through which it falls upon the sill, substantially as described. 70

3. In a device of the class described, a swinging sash, a channel member having a flat portion countersunk in the outer base portion of said sash, and an upper and a lower flange portion inclined outwardly and 75 downwardly therefrom, an elongated gutter secured to said sill and extending upwardly therefrom a sufficient distance to be engaged by the outer base portion of said sash, a downwardly inclined bottom for said gutter 80 containing a plurality of elongated openings near the outer edge thereof, and a flange extending upwardly from the outer edge of said gutter, into the interior of said channel member well below the upper flange portion of the 85 latter, an opening provided between the flange portion of said gutter and the countersunk portion of said channel member, through which water forced against the latter may drop upon its lower flange portion, said last 90 named flange portion being inclined outwardly and downwardly a sufficient distance to direct said water to the slotted portion of said gutter, through which it falls upon said sill, substantially as described. 95

4. In a device of the class described, a swinging sash, a channel member countersunk in the outside base portion thereof, a stationary sill for said sash, an elongated gutter secured to said sill and extending upwardly therefrom a sufficient distance to be engaged by the outside base portion of said sash, a downwardly inclined bottom for said 100 gutter containing an opening for the release of water therefrom, a flange extending upwardly from the bottom of said gutter, to the interior of said channel member, and a pair of flat metallic brackets secured to each side of the window frame, for clamping the gutter in a position for maintaining its 105 flange portion in close proximity to the countersunk portion of said channel member, whereby an opening is provided to admit water to the gutter, substantially as described. 110

In testimony whereof I have hereunto set my hand this 28th day of October, 1915. 115

OTTO M. BLIZZARD.
